UNITED STATES PATENT OFFICE.

URIAH S. JACKSON, OF OSSIPPEE, NEW HAMPSHIRE, ASSIGNOR TO THE SUPERIOR AUTOMATIC TELEPHONE CO., OF BOSTON, MASSACHUSETTS, A CORPORATION OF MAINE.

TELEPHONE-SERVICE APPARATUS.

No. 859,884.

Specification of Letters Patent.

Patented July 9, 1907.

Application filed August 18, 1905. Serial No. 274,781.

To all whom it may concern:

Be it known that I, URIAH S. JACKSON, a citizen of the United States, of Ossipee, in the county of Carroll and State of New Hampshire, have invented a new and 5 useful Improvement in Telephone-Service Apparatus, of which the following, taken in connection with the accompanying drawings, is a specification.

My invention relates to what are known as two-wire (either two wires or one wire and ground) party-line 10 telephone systems and apparatus, and is characterized by the fact that the several telephones of the line are included in closed loops tapped in a normally closed "calling" circuit, and consequently are normally short-circuited. In mode of operation the "calling" 15 circuit is, together with the loops in which the calling and called telephones are included, utilized as the talking circuit, all telephones other than the calling and called remaining short-circuited. Each telephone-station is equipped with a manually operable device to 20 open the normally closed talking circuit at the calling station, and also with make-and-break contact-mechanism the operation of which opens the talking circuit at the called station, whereby a talking circuit between the calling and called stations is established, all 25 other telephones remaining short-circuited. To prevent the talking circuit, when in use, from being cut into, interfered with, or listened into, the equipment of each station includes a lock-out means to lock from operation all stations except the two in use.

30 The invention and the means for accomplishing the purposes stated are fully hereinafter set forth. That which is regarded as new will be set forth in the claims appended to the description.

In the accompanying drawings, illustrating an apparatus embodying the invention:—Figure 1 is an elevation of the inclosing box, the transmitting and receiving instruments and the batteries; Fig. 2 shows the same parts, the door of the box being open thus displaying the interior construction of the operating parts; Figs. 40 3 and 4 show in elevation details of construction; Fig. 5 illustrates the method of working.

For obvious reasons some of the details are omitted and the reference letters are not all used.

In the drawings, the box is indicated by A and its 45 cover by A¹. The local telephone batteries are indicated by F—F and the bell-ringing battery by B. There are as many of these boxes and their batteries as there are users in the system and each user has a number for his box or station. One set of line batteries 50 L will do for the entire system. These line batteries are preferably of the kind known as closed circuit batteries and the circuit in which they are included may be termed the "calling" circuit. In the present system, there are fourteen of these boxes, each of which is

indicated by a numeral on the dial D, Figs. 1 and 2. 55 A pointer D¹ moves on the dial D and is made to indicate to the user that the desired or called box is in connection and its user may be communicated with.

I will now describe the mechanism by which the calls are made: The lever S which may be called the 60 winding lever is rigidly attached to the shaft S², and the said shaft S² has fixed upon it a drum S⁷ and a notched wheel S⁴, as shown in Fig. 4; a coiled spring, one end of which is shown as S¹⁴, is attached to the post a, and the other end to the drum S⁷. A pawl S⁵ is 65 attached to the spur gear S⁶ and is constructed to engage with the said notched wheel S⁴, this arrangement allows the notched wheel to be turned, by the depression of the winding lever S, in the direction of the arrow Z without turning the spur gear S⁶. This action 70 of turning the notched wheel S⁴ and with it the drum S⁷ winds up the spring S¹⁴, as one end of it is attached to the drum S⁷, and it is evident that the reaction of the said spring will give motion to the spur gear S⁶ in the opposite direction, that is, in the direction indicated by the arrow Z¹. This action will take place 75 whenever the lever S is depressed. The lever is returned to its normal position by the stress of the spring S¹⁴ which also rotates the spur gear S⁶ in the direction of the arrow Z¹.

The spur gear S⁶ communicates motion to the pinion T and the shaft C¹, thence to the contact make-and-break wheel C², see Figs. 2 and 3. The train T¹ T² and T³ and the escapement device T⁴ T⁵ and T⁶ have no function except to prevent the make-and-break 85 wheel C² from rotating too rapidly.

The number of contact points on the wheel C², Fig. 3, is equal to the numerals or divisions on the dial D and to the number of the boxes in the system. A post S¹⁵ extends downward from the make-and-break 90 wheel C² and serves as a stop for said wheel as it comes in contact with the end S¹ of the winding lever S when the said lever is in its normal position as indicated by dotted lines Fig. 3, and in full lines in Fig. 2; that is, the wheel C² is stopped when it has brought the pointer 95 D¹ on the fixed dial D to "0" on said dial.

To cause the make-and-break wheel C² to stop when it has made a sufficient number of electrical contacts between the electrodes l⁶ and l⁷ to cause the required 100 station to be called by the action of the trunnion pinion D³ as will be explained, I have the following-described device. To the shaft C¹, a ratchet wheel C³ is rigidly attached; this ratchet wheel has the same number of teeth that the contact wheel C² has contact points; see Fig. 3. A disk C, see Figs. 1 and 3, also 105 mounted on the shaft C¹, but free to rotate upon it, has on its under side a pawl C⁴ mounted upon a stop pin C⁶; this stop pin extends below the pawl C⁴ and serves,

when it comes in contact with the hook on the end of the controlling and releasing lever C⁷, to hold the said disk C from further rotation. The said lever C⁷ is pivoted at C⁸. The rotatable disk C has a handle or 5 knob C⁵ for turning and also an arrow or pointer C⁹ for indicating by the fixed dial C¹⁰ the number of the station to be called, that is, by turning the disk so that the arrow C⁹ will indicate the number of the station to be called, the pawl C⁴ will pass by a certain number of 10 teeth on the ratchet C³ according to the station to be called, the locking lever C⁷ being lifted, to allow this operation:—and this action will take the stop pin C⁶ so far away from the hook of the controlling lever C⁷ that the make-and-break contact wheel C² may rotate, 15 before being stopped by said hooks, sufficiently to make the required number of electrical contacts to operate the trunnion pinion D³ to the extent required to open communication with the station desired. The above-described movements are dependent upon the 20 action of the coiled spring S¹⁴ which operates the drum S¹ and the spur gear wheel S⁶, and relate to the operation of the electric make-and-break electrodes l⁶ and l⁷ which I will now describe together with their function.

The battery L is the line or calling circuit battery 25 and is of that class that is known as the closed-circuit battery. The circuit system consists of a normally closed circuit for operating the station-calling apparatus and closed local loop circuits for the telephone transmitters and receivers. This circuit, dominating 30 and causing the batteries F—F to act through their own circuit, may be described as follows: Starting from the battery L, Fig. 2, the main line L¹ connects all of the station boxes in series as shown in Fig. 5. The relay circuits at and within the boxes are the same 35 for all. One of these circuits will be described by reference to Fig. 2. The line wire enters the binding post L², thence by the wire l¹ l² to the relay magnet E, thence by l³ l⁴ to binding block l⁵, thence to the 40 spring electrode l⁶, to the spring electrode l⁷ (when these electrodes are in contact), thence by wire l⁸ l⁹ l¹⁰ to binding plate l¹¹, thence by spring electrode l¹² thence (when the electrode l¹² is in contact) to contact block l¹³, to the wire l¹⁴ l¹⁵ to binding post L³, thence to line L⁴ to battery L. The action of the last-described 45 circuit on the local-calling circuit is as follows: The said local-calling circuit starts from the open circuit batteries F—F through the wires m¹ m² to magnets at large M, Fig. 2 (see Fig. 4 and in dotted lines in Fig. 3), thence by m³ to block m⁴, coiled-spring electrode 50 m⁵ to electrode plate E³ (attached to the armature E¹, but insulated from it), thence to fixed plate m⁶ when armature E¹ is released, thence by wire m⁷ m⁸ to batteries F—F. Through this circuit the step-by-step movement of the pinion wheel D³ is operated and 55 movement is given to the pointer hand D¹ on the fixed dial D. The electro-magnet M is energized by the current through the circuit from the batteries F—F. An armature M¹ pivoted at n, Fig. 4, and retracted by the coiled spring n¹ has attached a double-acting sliding pawl M² having pawl points M⁴ M⁵. The action of 60 the magnet when energized is to swing the pawl in one direction, and that of the spring n¹ (when the magnet is not energized) to swing the said pawl in the other direction; this back-and-forth motion of the pawl M² serves to give a step-by-step motion to the trunnion 65

pinion D³. The trunnions of this pinion are indicated by D⁴ D⁴. The pointer hand D¹ is attached to the shaft D² of the pinion D³ so that a back-and-forth motion of the double pawl M² will cause the pointer hand D¹ to move one division on the fixed dial D, that is, one back-and-forth completed motion of the said pawl will cause the pointer hand to move from "0" to "1" and the next such motion from "1" to "2". One of these step-by-step motions takes place (caused by the 70 batteries F—F) at each time a contact is made by the 75 armature plate electrode E³ with the fixed electrode plate m⁶, that is, upon each release of the armature E¹ by the magnet E in the circuit of the line-closed circuit battery L.

The telephone circuit may be termed a closed supplemental or loop circuit from the circuit of the normally closed line or calling circuit battery, already described, and consists of the wire l¹⁷, from the electrode l⁷, the contact plate H¹ the wire l¹⁸ l¹⁹ to transmitter l²⁰, thence by wire l²¹ l²² l²³ to binding post R¹, thence 80 through receiver to binding post R², wire l²⁴ to fixed plate H³, thence by wire l²⁵ l²⁶ l²⁷ l²⁸ to fixed plate l¹³, wire l¹⁴ l¹⁵ to binding post L³, wire L⁴ to battery L. Normally, and when a telephone instrument is not in use, contacts H¹ and H² are closed, and the talking circuit passing through the instrument not in use has two paths, one from binding post L² through relay E, contact springs l⁶, l⁷, spring l¹², block l¹³, wire l¹⁴ to binding post L³; the other from binding post L² over same route to contact spring l⁷, thence by wire l¹⁷, contact arms H¹, H², wires l²⁵, l²⁶, l²⁷, l²⁸, block l¹³, to binding post L³. Normally the current will divide through both paths, but should a party not called remove his receiver from the hook, the first circuit will be opened at l¹², block l¹³, the inner end of the receiver hook being 90 withdrawn from contact l¹², and the current will then pass entirely through the second circuit. It will thus be observed that the springs H¹, H² short circuit the receiver and transmitter of any instrument not called, and therefore prevent the talking circuit being listened 95 into. There are two devices for breaking the circuit through the electrodes H¹ H² and establishing a telephone circuit through the plate electrode H¹, wire l¹⁸ l¹⁹ to transmitter l²⁰, etc. The first consists of the 100 bent lever N N² (pivoted at N¹) controlled by the manually operable lever S. The upper end of this lever N, N² except when lever S is in raised or initial position rests against the electrode H² and will hold the same out of electrical contact with the other or plate electrode H¹ for the reason that the bent lever N N² 110 has a strong spring N³ which will force the end N² upward and thus keep the contact point of the electrode H² away from the corresponding point of the plate electrode H¹, thus keeping the telephone-loop circuit in use; but when the lever S is in its raised or normal resting position, then the pin S³ engages the lower arm N of the lever N N², and thus causes the upper arm N² to be depressed, thus allowing the electrode H² to 115 make contact with the electrode H¹ (see middle instrument, in Fig. 5) and short circuiting the local talking circuit. The other device for separating the electrodes H² H¹ consists of a pin H on the pinion D³ (see Fig. 3). This pin is so located that when the pointer hand D¹ is on the number that indicates the number of the box in which it is placed then the short circuit at 120 125 130

contacts H' , H^2 is broken and the loop or telephone circuit is established and the telephone of this box can be used. The location of the pin H on the pinion is different for each box: for instance, in box No. 1 the pin H is 5 so placed that when No. 1 is called, it, the pin, will place the telephone circuit in use when the hand is on No. 1. And in No. 6 the pin is so placed that it will place the loop or telephone circuit in use when the hand is on No. 6 of the dial, and so on.

10 A separate battery B is used for the bell of each station. The bell circuit and its connected parts may be described as follows: The wire b b^1 b^2 b^3 b^4 b^5 b^6 takes the current from the battery to the electrode B^2 , Fig. 2, and through the drop latch B^4 to the electrode B^3 15 (when the said drop latch B^4 is raised up by the latch H^2), thence to the fixed electrode B^3 and the wire b^7 to the bell. The circuit is completed by the wire b^8 b^9 b^{10} b^{11} , switch plate b^{12} , contact pin b^{13} , spring plate b^{14} , pin b^{15} (in the telephone hanging lever R^3), spring 20 plate b^{16} , wire b^{17} b^{18} , back to battery B . It will be noticed that the above bell circuit may be cut or opened in three places, viz: at the drop latch B^4 when it is not held up by the action of the pin H acting through the electrode H^2 ; and at the switch b^{12} when 25 the push pin B^5 is forced up by the user; and also by the telephone hanging lever R^3 , that is, when the lever is drawn up by its spring (as it will be when the telephone receiver R is taken off), the pin b^{15} will be out of contact with the spring plates b^{14} and b^{16} .

30 The operation may be explained as follows, all the telephones being initially or normally short-circuited. If user at station 1 wishes to call station 6 he turns disk C until stop-pin C^6 is at 6 on dial C . Then he depresses lever S winding up spring S^{14} and permitting 35 lever N , N^2 to open the short circuit and establish the telephone circuit at station 1. The spring S^{14} gives motion to the make-and-break wheel C^2 . This wheel C^2 will rotate until the pointer D^1 has moved to No. 6 on the dial, that is, the double pawl M^3 will have operated in all of the boxes and set all of the trunnion pinions ahead six numbers as has been explained. This 40 action will cause the pin H of box No. 6 to break the contact between the electrodes H^2 and H^1 and thus cause the current to pass to the loop or talking circuit, 45 that is, the current will pass through the electrode plate H^1 , wire l^{18} and l^{19} to the transmitter l^{20} thence through wire l^{21} l^{22} and l^{23} to telephone receiver post R^1 and thence to the receiver R and the post R^2 , thence by wire l^{24} to electrode plate H^3 , thence by wire l^{25} l^{26} 50 l^{27} and l^{28} to plate l^3 , thence by l^{14} l^{15} to post L^3 and to the closed circuit battery L . Thus the user at station "1" may communicate with station No. "6" as desired.

If we assume that the person calling is at station No. 55 1, that is, the left-hand one on Fig. 5, his receiver R will be placed in the "loop circuit" by the action of the lever S , which he depresses at the outset. This depression of the lever S frees the lever N , N^2 which in turn throws up the electrode H^2 , separating it from the 60 contact-ledge formed at the lower end of the electrode H^1 , and breaks the short circuit and brings in the "loop circuit," while at the station called (that is, the station on the right of Fig. 5) the step-by-step motion of the trunnion-wheel D^3 will bring the pin H to such a

position that it will lift up the electrode H^2 and thus 65 break the short circuit and bring the loop circuit into service of both the caller and the one called, and prevents short-circuiting of either telephone. The same movement of pin H will close the local ringing circuit at B^3 B^4 , and the bell at the called station will continue 70 to ring till the party called removes his receiver from the hook, or until the calling party replaces his receiver on the hook.

The mechanism at all the stations not in use is locked 75 from operation by the hooked end S^9 of lever S^{10} S^{11} , which engages a pin S^3 on lever S , preventing the operation of said lever S , until released therefrom, by finger S^8 of the trunnion wheel D^3 lifting arm S^{11} of the lever and withdrawing S^9 from engagement with S^3 ; and this occurs only when the index D' is at "0." 80

To restore the apparatus to its normal condition, the user raises the outer end of the lever C^7 by doing which he frees the pin C^6 from the hook of the lever, and thus allows the rotation of the make-and-break wheel C^2 to continue until the pin S^{15} comes in contact with the 85 end S^1 of the lever S and thus stops all of the rotating parts with the pointer hand at "0" as desired.

From the foregoing description it will be observed that according to my invention the several telephones are included in closed loops tapped in a normally 90 closed calling circuit and are normally short circuited. The equipment of each telephone at each party station includes a manually operable device which opens the normally closed short circuit and establishes the talking circuit of that station, and also with a make and 95 break contact mechanism, the operation of which breaks or opens the short circuit at a selected or called station, establishing the talking circuit of that station, and the telephone loop circuits of the called and calling stations are then in circuit with the line circuit. All 100 other telephones on the line are unaffected and remain short-circuited. Combined with the foregoing mechanism, the equipment of each telephone is provided with a lockout means, whereby all the telephones except the calling and the called are locked out and cannot be operated, whereby the talking circuit between the calling and called stations cannot be interrupted and listening in is prevented. 105

Claims.

1. In a telephone service apparatus a call device consisting of a circuit make-and-break wheel; a winding lever the movement of which by the operator will incite a rotative movement in the said wheel; a step-by-step switch mechanism operated by said make-and-break wheel; an indicating disk having a pointer and stop pin attached; a 110 fixed dial having numbers so arranged that by setting the said pointer at any determined number, a telephonic connection is made with the station corresponding with the said number; and a let-off lever constructed to allow the moving parts to restore the entire apparatus to its normal 115 condition, that is, with all the pointers at "0"; substantially as and for the purpose set forth.

2. In a two wire party line telephone service apparatus, a normally closed calling circuit, a plurality of telephones included in closed normally short circuited 125 loops tapped in the calling circuit, a manually operable device at each telephone station adapted to break the normal short circuit and establish the talking circuit of that station, each telephone also provided with a make and break contact mechanism the operation of which breaks 130 the short circuit at a called station and establishes the talking circuit of that station, substantially as described.

3. In a two wire party line telephone service apparatus, a normally closed calling circuit, a plurality of telephones included in closed normally short circuited loops tapped in the calling circuit, a manually operable device at each telephone station adapted to break the normal short circuit and establish the talking circuit of that station, each telephone also provided with a make and break contact mechanism the operation of which breaks the short circuit at a called station and establishes the talking circuit of that station, and a lock out means at each tele-

phone station arranged to prevent operation of said manually operable device of all the telephone stations.

In testimony whereof, I have signed my name to this specification in the presence of two subscribing witnesses, on this 11th day of August A. D. 1905.

URIAH S. JACKSON.
